SLIP ELEVATOR CONSTRUCTION

Herbert Edmund Grau, Pasadena, Chester Albert Lundein, Los Angeles, and Gird Elmer Mulinix, South Gate, Calif., assignors to Byron Jackson Co., Los Angeles, Calif., a corporation of Delaware

Application December 26, 1935, Serial No. 56,164

18 Claims. (Cl. 24—263)

This invention relates to elevators for raising and lowering pipe, rods and the like in wells and has to do more particularly with slip type elevators which grip the pipe or rod itself instead of merely engaging the under side of a collar or coupling on the pipe.

An object of the invention is to automatically lift the slips of a slip elevator out of pipe-engaging position in response to opening of the elevator.

Another object is to provide a simple and effective structure for forcing the slips in opposite sides of an elevator to move simultaneously into and out of pipe engaging position.

Another object is to provide a slip elevator in which the slips are maintained entirely clear of a pipe encircled by the elevator until the slips are released to engage the pipe, thereby preventing wear on the slip teeth which would otherwise result from sliding of the elevator up or down along the pipe prior to setting of the slips.

Another object is to provide a slip elevator in which the pipe-engaging teeth on the slips are maintained clear of a pipe within the elevator even after being released if the elevator is moved downwardly along the pipe while at the same time the slip teeth are immediately forced into gripping engagement with the pipe in response to upward movement of the elevator along the pipe.

Another object is to automatically and positively force the slips of a slip type elevator into pipe-gripping position in response to movement of the elevator upwardly along a pipe into a position adjacent the collar or coupling on the upper end of the pipe.

The manner in which the foregoing together with other more specific objects of the invention are obtained, will appear from the following description.

As is well known to those familiar with the art, slip elevators of the class to which this invention relates, whether they be of the center latch or side door type, comprise a pair of hinged members adapted to encircle the pipe when closed and adapted to swing apart to permit placing on or removal from a pipe. It is also necessary after closing the hinged body members about the pipe to release the slips into wedging position between the body member and the pipe. However, it is also necessary that the slips be retained out of pipe-engaging position until after the body members are locked in closed position about the pipe, else it may be difficult or even impossible to close and lock the members.

In accordance with the present invention, we satisfy the foregoing requirements by providing a cam mechanism which operates in response to opening movements of the body members of the elevator to retract the slips and provide a latching mechanism for thereafter retaining the slips in retracted position until it is desired to set them. As a result, the slips are always retracted when the elevator is removed from one pipe and remain retracted during placing and locking of the elevator about the next pipe.

For releasing the slips we provide a trigger or latch mechanism which may be actuated automatically in response to contact with a collar or external upset, or any lateral projection on the upper end of the pipe, or may be actuated manually through a line. We effect positive operation of the slips by so designing the latching mechanism that releasing movement thereof directly forces the slips downward into wedging relation between the pipe and the body members of the elevator.

Wear of the slip teeth caused by the sliding movement of the elevator along the pipe is prevented in accordance with the invention by providing buffer members resiliently supported on the individual slips, which buffer members contact the pipe and resiliently urge the slips away from the pipe. When the slips are set, however, these buffer elements are forced back into recesses provided therefor in the slips, permitting the slips to engage the pipe.

For purposes of explanation, some preferred embodiments of the invention as incorporated in a center latch elevator will now be described in detail with reference to the drawings. It is to be understood, however, that many features of the invention are equally applicable to side door elevators and that the invention is not to be limited to elevators of center latch construction.

In the drawings:

Fig. 1 is a perspective view of a center latch slip elevator in accordance with the invention;

Fig. 2 is a detail sectional view illustrating the latch mechanism for locking the two halves of the elevator together in closed position;

Fig. 3 is a horizontal sectional view taken at the level III indicated in Fig. 1;

Fig. 4 is a detail horizontal sectional view taken at the level IV in Fig. 1;

Fig. 5 is a detail perspective view illustrating the cam action for lifting the slips;

Fig. 6 is a detail view taken along the lines VI—VI in Fig. 3;

Fig. 7 is a detail vertical section illustrating the operation of the tripping mechanism of the elevator, showing the elevator with the slips in retracted position; and

5 Fig. 8 is a view similar to Fig. 7 but showing the slips released into pipe-engaging position.

Referring to Fig. 1, the elevator therein depicted comprises two main body members 1 and 2, respectively, which are hinged together at one 10 end of each member by a hinge pin 3. As shown in Fig. 1, the two members 1 and 2 are in open position ready to be placed about a pipe. After being placed about a pipe the two members 1 and 2 are brought together as by the handles 4 15 and 5 thereon and locked in closed position by a latch 6 which engages lips 7 and 8, respectively, on the two body members 1 and 2. The particular latch construction disclosed is old and does not constitute a part of the present invention.

20 It will suffice to say that it is pivoted to the body member 1 by a hinge pin 9 and urged into closed position by a helical spring 10. After it has been moved into engagement with the lips 7 and 8, it is locked in that position by a latch 11 pivotally mounted by a pin 12 on the member 6 and having a latch bolt 13 which engages a recess 14 provided therefor in the lip 8. The latch mechanism described positively restrains the two body members 1 and 2 against separating movement and is made sufficiently heavy to withstand the greatest separating strains to which the elevator may be subjected.

For the purpose of supporting the elevator and a pipe suspended therefrom, ears 15 and 16 are 35 provided projecting from the opposite sides of the members 1 and 2, respectively. Since the particular construction of these ears does not constitute a part of the present invention, they have been shown partially broken away in Fig. 3.

40 Each of the body members 1 and 2 is provided on its inner surface with a seat 17 slidably supporting two of four slips 18, 19, 20 and 21. As shown in Figs. 7 and 8, the surfaces of the slip seats 17 are conical in shape and converge at 45 their lower ends. The cooperating surfaces of the slips are also conical in shape and curved to correspond approximately with their associated seating surfaces when they are in pipe-engaging position, as shown in Fig. 8.

50 It will be observed that in cross section each slip is wedge-shaped so that its pipe-contacting face 22 may contact with a pipe over its full length. Of course, the slips have their pipe-contacting faces cylindrically curved to correspond to the size pipe with which they are intended to be used. To secure the slips 21 in position against their respective seats 17, a retaining pin 23 is provided for each slip. Each pin 23 extends through a hole 24 provided therefor in the elevator body member in which it is positioned, the pins being inserted from the top and retained in position by flanges 25 on pipe guides or bushings 26 which are bolted to the tops of the two body members 1 and 2, respectively. A small aperture 55 27 may be provided in the body members below the lower ends of the pins 23 to permit driving the pins upwardly and outwardly to facilitate replacing slips. Each pin 23 may also serve to secure in position a lower pipe-contacting bushing 28. The upper and lower pipe-contacting bushings 26 and 28 are so dimensioned with respect to the size pipe with which the elevator is to be used as to prevent any substantial lateral movement of the elevator with respect to the pipe when the elevator is in closed position.

The pins 23 also pass through ears 30 on the seating faces of the slips and thereby retain the slips adjacent their seats. In order to provide room for the ears 30, the center lower portion of each slip seat 17 is cut away to define a recess 31 5 in which the ears 30 are free to move up and down.

It is sometimes desirable to resiliently urge the slips into seating position. To this end, a helical spring 32 may be provided around each pin 23 10 between the upper ear 30 thereon and the cooperating body member. However, it is to be understood that it is not essential that springs 32 be employed as in many instances the force of gravity acting upon the slip is sufficient to seat 15 the slip. As will be brought out more in detail later, we also provide a mechanism for positively setting the slips so that it is not even necessary that the slips be urged downwardly by gravity.

By virtue of the fact that the cooperating surfaces of the slips and seats are conical, they can only contact uniformly over their entire surfaces in one position. Therefore, in order to permit free sliding movement of the slips on their associated pins 23, the apertures in the ears 30 for the pins 23 are made appreciably larger than the pins so that there is considerable free lateral movement of the slips with respect to the pins.

It is quite essential in a slip elevator of the general type described that all of the slips move 30 simultaneously into and out of seating position. To this end, the two slips in each body member 1 and 2, respectively, are linked together for simultaneous vertical movement by providing a recess or notch in one edge of one slip and a cooperating 35 tongue projecting from the juxtaposed edge of the other slip. Thus referring to Fig. 3, it will be observed that the slip 20 is provided with a notch 40 projecting therefrom, (this notch being shown more clearly in Fig. 5), which notch engages a 40 tongue 41 projecting from the edge of slip 21. Likewise the slip 19 is provided with a tongue 42 which projects into a notch 43 in the edge of the slip 18. It will be observed, therefore, that slips 18 and 19 must move upwardly and downwardly 45 together and likewise slips 20 and 21 must move upwardly and downwardly together.

To intercouple the slips in the two body members 1 and 2, respectively, for simultaneous vertical movement, other means must be employed because of the fact that the two body members 1 and 2 separate from each other during opening movement. The desired coupling is effected by providing an arcuate arm 44 of substantial length on the slip 20, this arm being concentrically positioned with respect to the hinge pin 3 and extending a substantial distance thereabout in the general direction of the opposite body member 1. The arm 44 intercepts the slip 19 in body member 1, the slip 19 being provided with a groove 45 to 60 slidably receive the arm 44. The arm 44 is therefore free to move longitudinally past the slip 19 in response to opening and closing movement of the body members 1 and 2, but forces the slips 19 and 20 to move vertically simultaneously, one with 65 the other. Since slip 19 is also coupled to slip 18 and slip 20 is coupled to slip 21, as previously described, it will be observed that all of the slips are constrained to move up and down simultaneously regardless of whether the elevator is in open or 70 closed position.

To raise the slips 18 to 21, inclusive, in response to opening of the elevator, the cam 46 is provided on the body member 1, the cam extending helically with respect to the hinge pin 3. The cam 75

46 intercepts the adjacent edge of slip 20 and the slip is recessed to receive the cam so that the upper inclined surface 47 of cam 46 bears against a shoulder 48 at the upper end of the recess 49 in 5 slip 20, (this construction being shown clearly in Fig. 5).

When the body members 1 and 2 are in closed position, the shoulder 48 rests upon the lower end of the cam surface 47, thereby permitting the slips 10 to assume their lowermost, pipe-engaging position shown in Fig. 8. However, as the body members are swung apart to open the elevator, the shoulder 48 on slip 20 is forced to ride upwardly along the inclined surface of the cam, thereby lifting the 15 slip 20, and of course simultaneously lifting the other three slips.

If no means were provided for securing the slips in uppermost position, they would fall into pipe-engaging position each time the elevator was 20 closed. In most instances, it is desired that the slips remain in retracted position after the elevator has been closed and be released either automatically or manually at a later time. Thus in some instances the elevator may be placed on the 25 pipe at a point some distance below the upper end thereof whereas it is desired that the elevator grip the pipe at a point higher up. We therefore provide a latching mechanism for retaining the slips in the uppermost position to which they have 30 been lifted by opening movement of the elevator.

This latching mechanism is shown in perspective in Fig. 1 and in section in Figs. 7 and 8. It comprises a housing member 50 bolted to the top of the elevator member 2 and extending thereabove an appreciable distance. This housing member 50 is provided with a slot-shaped recess at the upper end in which the bifurcated upper end of a supporting link 61 is positioned, which is formed integrally with the slip 21. The link 61 is 40 slidably supported within the member 50 for free vertical movement and for limited radial movement with respect to the axis of the elevator but is restrained against circumferential motion about the axis of the elevator. Supported between the 45 bifurcated upper ends of the link 61 by a pin 52 is a latch member 51. This latch member is constantly urged into the position shown in Fig. 7 by a helical spring 53 which fits in an arcuate slot 54 in the latch 51 and is compressed between one end wall 55 of the slot and a pin 56 anchored to the link 61. Latch member 51 is provided with 50 an arm or trigger 57 which extends almost but not quite into contact with a pipe positioned within the elevator, this pipe being indicated at 55 59 in Figs. 7 and 8. The end face 60 of arm 57 is preferably convexedly curved, in a vertical plane, concentrically with respect to the pin 52 and curved concavely in a horizontal plane about the central axis of the elevator so that 60 it conforms approximately to the curvature of the pipe 59.

The latch member 51 is also provided with an arm 62 having an eye hole 63 therein for the attachment of a line and having a shoulder 64 thereon adapted to rest against a stop member 65 on the housing 50. It will be observed that the portion of the arm 62 containing the eye 63 extends part way between the shoulder 64 and another shoulder 66 on the support 50. The latch 51 is normally supported vertically 65 by contact of the shoulder 64 with the shoulder 65 as shown in Fig. 7. In this position the latch, through link 61, supports the slip 21 in retracted position as shown in Fig. 7. Since as previously 70 described, all of the slips are connected together,

they will all be held in retracted position when the latch 51 is in the position shown in Fig. 7.

The slips may be released to engage the pipe by either of two methods. One method is to pull the arm 62 of latch 51 outwardly as by a 5 line looped through the eye 63. This disengages the shoulder 64 from the shoulder 65, as shown in Fig. 8, thereby permitting the latch link 61 and the slip 21 to drop into the lower position shown in Fig. 8 in which the slips are in engagement with the pipe 59.

When it is desired that the slips be released automatically, the elevator, after being clamped about the pipe, is lifted up along the pipe with the slips retracted as shown in Fig. 7 until the 10 arm 57 on the latch 51 impacts against the collar 70 on the upper end of the pipe 59. This causes the latch member 51 to rotate about the pin 52 as a fulcrum to force the link 61 and the slip 21 positively downward. After a limited 15 movement of the latch 51, the shoulder 64 slips off the shoulder 65, as shown in Fig. 8, and thereafter the slip 20 and link 61 are perfectly free to follow the slip 21 downward as far as the latter can go. If the slips should not drop downwardly when the latch 51 slips off of shoulder 65, the latch 51 will continue to rotate about the pin 52 until the ring 62 contacts the shoulder 66, whereupon further downward movement of the latch arm 57 forces the slips into engagement 20 with the pipe 59.

The latch arrangement described has particular utility in connection with oil wells which produce large amounts of paraffin. The paraffin produces a thick viscous coating on the pipe 25 or tubing as the latter is lifted out of the well and the paraffin is transferred from the tubing to the elevator, more or less completely filling all the spaces therewithin and preventing free movement of the slips. However, by employing 30 the latch mechanism described and operating it automatically by lifting the elevator until the arm 57 engages the collar on the pipe, the slips are forced positively into engagement with the pipe regardless of any resistance to free movement of the slip caused by the paraffin. 40

It is important to note, however, in connection with the automatic operation of the latch as described, that by virtue of the fulcrum effect on the shoulder 66, the end of the arm 57 travels 45 downwardly faster than does the slip 21 and the link 61. As a result, when the slips engage the pipe and dig into the latter, they are then carried a short distance downward into full seating position directly by the pipe, the slip moving 50 with the pipe. This causes the arm 57 to move downwardly faster than the pipe so that when the slips have been set the arm 57 is always 55 clear of the collar or coupling 70. Hence during the actual lifting or lowering operation none 60 of the weight of the pipe or tubing is transferred to the elevator through the collar and the latch arm 57.

Because of the difficulties in machining the parts and also by reason of the fact that the slip 65 seating surfaces are conical, the slips are always mounted rather loosely upon the pins 23, there often being sufficient play so that even when the slips are in retracted position as shown in Fig. 7, they may occasionally lightly contact a pipe as 70 the elevator is being slid along the pipe. This is very objectionable because it occasions rapid wear of the teeth 22 on the faces of the slip and if the sharp surfaces of the teeth 22 are dulled the slips may then fail to properly grip the pipe. 75

To prevent accidental contact of the slip teeth with a pipe, with the slips in retracted position as shown in Fig. 7, we prefer to provide a bow spring 80 on each slip, this spring being secured in a vertical recess extending along the face of the slip. The ends of the spring may be retained in grooves 81 positioned at the ends of the recesses in which the bow springs are mounted. The centers of the bow springs project out beyond the faces of the slips and contact the pipe as shown in Fig. 7, thereby exerting a spring action on the slip sufficient to take up lost motion on the slip 23 and move the teeth of the slip away from the pipe. However, when the slips are set in either one of the manners previously described, the bow springs 80 are simply compressed into their recesses in the slips as shown in Fig. 8 so that they do not effect the normal setting operation of the slips.

It is sometimes desired to lower the elevator along the pipe with the slips released, to grip the pipe at a point lower down. Downward movement of the elevator with the slips released is, of course, possible because the friction of the pipe on the bow springs tends to carry the slips upwardly along their seats, thereby releasing them from wedging action against the pipe. However, this practice is objectionable with ordinary elevator constructions because it occasions wear on the slip teeth as a result of the friction with the pipe. However, by employing the bow springs 80 as disclosed in Figs. 7 and 8, and making these springs sufficiently stiff, they alone will contact the pipe during downward movement of the elevator along the pipe and will keep the teeth of the slips clear of the pipe, thereby preventing wear on the teeth.

To simplify the explanation of the invention, the latter has been described as incorporated in a particular type of elevator. It is obvious to those skilled in the art that various features of the invention may be incorporated in elevators of slightly different construction and the invention is therefore to be limited only as set forth in the appended claims.

We claim:

1. A slip elevator of the type described comprising a pair of hinged pipe encircling members movable into closed and open positions and means for locking said members in closed position, the inner surfaces of said members having inwardly and downwardly inclined slip seats thereon, slips slidably supported on said seats for downward movement therealong into pipe-engaging position and upward movement therealong out of pipe-engaging position, and means actuated by said members for lifting said slips out of pipe-engaging position in response to opening movement of said members.

2. A slip elevator as described in claim 1, in which said means for lifting said slips comprises a cam on one of said members and a cam follower on the other member.

3. A slip elevator as described in claim 1, in which said means for lifting said slips comprises a cam on one of said members and a cam follower on one of said slips positioned on the other member, and means interconnecting all said slips for simultaneous movement.

4. A slip elevator of the type described comprising a pair of hinged pipe encircling members movable into closed and open positions and means for locking said members in closed position, the inner surfaces of said members having inwardly and downwardly inclined slip seats thereon, slips

slidably supported on said seats for downward movement therealong into pipe-engaging position and upward movement therealong out of pipe-engaging position, means actuated by said members for lifting said slips out of pipe-engaging position in response to opening movement of said members, and latch means for releasably retaining said slips out of pipe-engaging position during and following subsequent movement of said members into closed position.

5. A slip elevator of the type described comprising a pair of hinged pipe encircling members movable into closed and open positions and means for locking said members in closed position, the inner surfaces of said members having inwardly and downwardly inclined slip seats thereon, slips slidably supported on said seats for downward movement therealong into pipe-engaging position and upward movement therealong out of pipe-engaging position, means actuated by said members for lifting one of said slips out of pipe-engaging position in response to opening movement of said members, and means interconnecting all said slips for simultaneous vertical movement.

6. A slip elevator as described in claim 5 in which said means interconnecting one slip on one of said members to a slip on said other member comprises an arcuate arm on one slip, said arm being concentric with respect to the hinged axis of the elevator and slidably engaging a slip on the other member to restrain the latter against vertical movement with respect to said arm.

7. A slip elevator of the type described comprising a pair of hinged pipe encircling members movable into closed and open positions and means for locking said members in closed position, the inner surfaces of said members having inwardly and downwardly inclined slip seats thereon, slips slidably supported on said seats for downward movement therealong into pipe-engaging position and upward movement therealong out of pipe-engaging position, a pipe-contacting member for each slip, and means for yieldingly supporting each pipe-contacting member forward of the face of its associated slip, each contacting member being retractable past the pipe-contacting face of its associated slip in response to pressure exerted thereon.

8. A slip elevator as described in claim 7, in which the slips are loosely slidably supported on their seats whereby they are capable of a limited amount of radial movement inwardly away from their seats.

9. A slip elevator as described in claim 7, in which the slips are loosely slidably supported on their seats whereby they are capable of a limited amount of radial movement inwardly away from their seats, and in which said pipe-contacting members function when the elevator is positioned on a pipe to resiliently urge the slips away from the pipe and against their seats.

10. A slip elevator as described in claim 7, in which said pipe-contacting members comprise bow springs mounted in vertical recesses provided therefor in the faces of the slips, the bow springs being positioned with their convex sides inwardly toward a pipe contained within the elevator and the ends of the springs being supported in the ends of the recesses.

11. A slip elevator of the type described comprising a pair of hinged pipe encircling members movable into closed and open positions and means for locking said members in closed position.

- tion, the inner surfaces of said members having inwardly and downwardly inclined slip seats thereon, slips slidably supported on said seats for downward movement therealong into pipe-engaging position and upward movement therealong out of pipe-engaging position, means actuated by said members for lifting said slips out of pipe-engaging position in response to opening movement of said members, latch means for releasably retaining said slips in uppermost position and trigger means associated with said latch in such position as to be engaged by a projection on the upper end of a pipe encircled by the elevator when the latter is moved up along the pipe for releasing said latch means in response to contact of the trigger with the pipe projection.
12. A slip elevator of the type described comprising a pair of hinged pipe encircling members movable into closed and open positions and means for locking said members in closed position, the inner surfaces of said members having inwardly and downwardly inclined slip seats thereon, slips slidably supported on said seats for downward movement therealong into pipe-engaging position and upward movement therealong out of pipe-engaging position, means actuated by said members for lifting said slips out of pipe-engaging position in response to opening movement of said members, latch means mounted on one of said slips and cooperating with the member on which that slip is mounted, for releasably retaining said slips in uppermost position, and trigger means associated with said latch for releasing the latter.
13. A slip elevator as described in claim 11, with means connecting said trigger to said slips whereby downward movement of said trigger positively moves said slips downward into pipe-engaging position.
14. A slip elevator as described in claim 12, in which said latch and trigger means comprises an arm secured to and extending upwardly from one of said slips, a lever member fulcrumed upon the upper end of said arm, said lever means comprising an arm extending toward the surface of a pipe engaged in the elevator and another arm extending substantially in the opposite direction, stationary means on said elevator for engaging said last mentioned arm in one position of said lever means, spring means for urging said lever means into said last mentioned position, said lever means being so mounted that downward movement of said first mentioned arm thereon disengages said second mentioned arm from said stop member whereby said arm and slip are released for free downward movement.
15. A slip elevator as described in claim 12, in which said latch and trigger means comprises an arm secured to and extending upwardly from one of said slips, a lever member fulcrumed upon the upper end of said arm, said lever means com-

prising an arm extending toward the surface of a pipe engaged in the elevator and another arm extending substantially in the opposite direction, stationary means on said elevator for engaging said last mentioned arm in one position of said lever means, spring means for urging said lever means into said last mentioned position, said lever means being so mounted that downward movement of said first mentioned arm thereon disengages said second mentioned arm from said stop member whereby said arm and slip are released for free downward movement, and a second frame member on said elevator positioned above said last mentioned arm on said lever member and adapted to be engaged thereby in response to downward movement of said first mentioned arm for forcing said arm and slip into lowermost position.

16. A slip elevator of the type described comprising a pair of hinged pipe encircling body members movable into closed and open positions, the inner surfaces of said members having inwardly and downwardly inclined slip seats thereon, slips on said seats, pins for slidably retaining said slips on said seats, pipe-contacting bushings on said body member above and below said slips, respectively, said body members having holes for receiving said pins, extending from one end of the body member almost to the other end, the bushing at said one end overlying the open end of said hole whereby it prevents escape of the pin therein, and means for retaining said bushings on said body members.

17. A slip elevator as described in claim 16, in which the bushing at said other end of the body member has an apertured tongue engaged by said pin whereby the bushing is retained in place by the pin.

18. A slip elevator of the type described comprising a pair of hinged pipe encircling body members movable into closed and open positions, the inner surfaces of said members having inwardly and downwardly inclined slip seats thereon, slips on said seat, pins for slidably retaining slips on said seats, pipe-contacting bushings on said body members above and below said slips, respectively, said upper pipe-contacting bushings overlying the upper ends of said pins to prevent longitudinal escape upwardly of the pins from the body members, means for securing the upper bushings on their associated body members, and means on the lower bushings for retaining them on their associated body members comprising apertured tongues intercepted by said pins whereby the lower bushings are retained in place by the pins.

HERBERT EDMUND GRAU.
